(57) **CLAIM**

The ornamental design of a mouse-type input device, as shown and described.

DESCRIPTION

FIG. 1 is a perspective view showing my new mouse type input device;

FIG. 2 is a front view thereof;

FIG. 3 is a back view thereof; and

FIG. 4 is a left side view thereof, the right side view thereof being a mirror image of that which is shown;

FIG. 5 is a top side view thereof; and,

FIG. 6 is a bottom view thereof.

The broken lines are for illustrative purposes only and from no part of the claimed design.
